BRICKMAKING MACHINE

Joseph J. Mandryl, Brooklyn, N. Y., assignor to
Brickmaster, Inc., New York, N. Y., a corpora-
tion of New York

Application December 13, 1947, Serial No. 791,543

8 Claims. (Cl. 25—99)

1

This invention relates to brick-making machines and more particularly to machines of the type described in Dietrichs United States Letters Patent No. 1,782,413, patented November 25, 1930. The invention aims to provide certain improvements in brick-making machines of this type, and in particular to provide novel and improved troweling and tamping agencies and improved pallet discharging means.

The brick-making machine to which the invention relates has a conveyor of pallet-carriers for continuously carrying brick-supporting pallets through various brick-making operations involving feeding, troweling and tamping of the brick material in molds formed on each pallet by upstanding transverse backs secured to each pallet-carrier and a plurality of longitudinal and equally spaced stationary divider bars positioned intermediate and similarly spaced from two outer stationary side plates. Throughout this specification and the appended claims that end of the machine at which the brick material is fed to the molds on the pallets is referred to as the forward end and that end of the machine at which the pallets loaded with molded brick are discharged is referred to as the rear end.

According to one aspect of the invention, the height of the divider bars from their forward ends rearwardly to the stage of final brick formation is substantially less than the contemplated thickness of the brick to be molded while the height of the bars rearwardly over their remaining length is higher than the contemplated thickness of the brick is to be molded. The point of height change is abrupt, and the upstanding edge of the bar at the point of height change is advantageously beveled and forwardly inclined. Just rearwardly of the point of height change in the divider bars, an individual final trowel for each brick mold is provided. These trowels have a common support, and novel means are provided for adjusting the angle of contact of the trowels with the upper surface of the brick to be troweled.

According to another aspect of the invention, improved rotary tamping and troweling means are provided rearwardly of the feed of the brick material to the molds. This means comprises rotary blades of such contour and angular disposition as to push and press the brick material into the sides and corners of the outer molds where the pressure of the feed does not reach. Rearwardly of the rotary blades are novel and improved rotary tamping paddles spanning transversely several brick molds.

2

According to a further aspect of the invention, the final tamping of the molded bricks is imparted by a relatively narrow tamping plate spanning all of the molds of the pallet, which is confined between two vertically-disposed plates and rapidly reciprocated in a substantially vertical plane by virtue of a novel pivoted link connection with its eccentric actuating means. Up to the stage just rearward of this tamper, the divider bars are of the aforementioned lower height which permits more effective and uniform tamping and troweling of the brick material in the molds, and a more uniform density of the material in the individual molds. Following the final tamping, the molded bricks are carried to that section of the divider bars of higher height and are individually subjected to a final troweling.

The foregoing and other novel features of the invention will be best understood from the following description taken in conjunction with the accompanying drawings, in which

Fig. 1 is a longitudinal section of a brick-making machine embodying the improvements of the invention,

Fig. 2 is a top plan of the machine,
Fig. 3 is a vertical section on the section line 3—3 of Figs. 1 and 2,

Fig. 4 is a vertical section on the section line 4—4 of Figs. 1 and 2,
Fig. 5 is a side elevation of a divider bar,
Fig. 6 is a section on the section line 6—6 of Fig. 5,

Fig. 7 is a partial sectional plan on the section line 7—7 of Fig. 1,
Figs. 8, 9 and 10 are detail views of the individual trowels and adjusting means therefor, and

Figs. 11, 12 and 13 are detail views of the rotary blades.

The drawings illustrate a brick-making machine of the type described in the United States patent of Dietrichs No. 1,782,413. This machine operates continuously to produce molded bricks and is especially adapted for the production of

molded concrete bricks. The machine has a plurality of pallet-carriers 10 having upstanding backs 11 and spaced upstanding supports 12 for supporting removable pallets 13 as they progress through the successive operating stages of the machine. The pallets are slightly wider than their carriers and hence extend a short distance beyond the side edges of the carriers (Figs. 3 and 4). The pallet-carriers 10 are secured to two endless link chains 14. Each chain 14 operatively engages a pair of sprockets 15 and 15' posi-

tioned at the opposite ends of the machine. The chains are positioned, in suitably spaced relation, intermediate the sides of the pallet-carriers and beneath the advancing pallet-carriers with their loads of molded brick and above the returning empty pallet-carriers (Figs. 2 and 3).

The pallet-carriers correspond in length to two links of the chain and successive carriers are centrally secured by saddle members 14' to corresponding alternate links of the two chains. Each of the sprockets 15 and 15' has 8 teeth and hence with each revolution of the sprockets the chains move through the length of four pallet-carriers. The sprockets 15 and 15' are keyed to rotatably mounted shafts 16 and 16' respectively. The shaft 16, at the discharge end of the machine, carries a sprocket 17 (at one end thereof) adapted to be driven by a chain 18 and cooperating sprocket 19 secured to a drive shaft 20 of the machine.

The endless chains and pallet-carriers secured thereto constitute a pallet conveyor. As each pallet-carrier passes around the forward sprockets 15' into a horizontal position, a pallet 13 is placed on the spaced supports 12 of the carrier. When the pallet-carriers arrive in the horizontal position adjacent one another, the distance between successive upstanding backs 11 is that corresponding to the length of the brick to be made and the vertical height from the upper surface of the pallet to the top of the back 11 corresponds to the thickness of the brick.

Each pallet-carrier has a plurality of backs 11 corresponding to the number of bricks to be molded per pallet. The backs 11 are fastened to the rear edge of the carrier in slightly spaced relation from one another, and longitudinal slicer or divider bars 21 extend through the spaces 11' between the individual backs from near the forward end of the machine to near the discharge end, the bars dividing the pallets lengthwise into sub-divisions corresponding to the width of the bricks. The continuously moving conveyor carries the pallets through the successive operations of brick-making, and delivers the completely molded bricks 22 to the discharge end of the machine. The machine illustrated in the drawings is designed to make six bricks on each pallet, but this number may be more or less. The brick-making operations comprise generally, (1) delivery of the cementitious or other mass, of which the bricks are composed, from a hopper 23 to the advancing pallets, (2) mixing, troweling, and tamping by rotary blades 24 and paddles 25, (3) troweling by a transverse bar 26, (4) tamping by a vertically reciprocating tamper 27 and (5) final troweling by individual trowels 28.

The operative elements of the machine are supported by a structural steel framework comprising two vertical side frame plates 30 and 31 resting on the ground or other foundation and tied together in spaced relation by two angle bars 32. Pairs of spaced uprights 33-34 and 35-36 are secured to the side frames 30 and 31, respectively. Two spaced transverse I-beams 37 are secured at their ends to the side frames 30 and 31 and support three spaced longitudinal I-beams 38 positioned directly beneath and forming a bed-support for the pallet-carriers 10. The lower surfaces of the pallet-carriers have sliding contact with the upper surfaces of the beams 38. The shafts 16, 16' and 20 are rotatably mounted in bearings 39 secured to the side frames. The blades 24 and the paddles 25 are secured to shafts 40 and 41, respectively, rotatably mounted in

bearings 39 secured to the side frames. The tamper 27 is suspended from a shaft 42 rotatably mounted in bearings 39 carried by the uprights 33 and 34.

The machine is driven by a pulley or the like 43 secured to one end of the shaft 42. A pinion 44 is secured to the other end of the shaft 42, and engages a gear 45 secured to one end of the shaft 41. The shaft 41 has a pinion 46 engaging a similar pinion 47 on the shaft 40 for driving the latter. The pinion 46 also engages a gear 48 on the shaft 20 for driving the latter. The sprocket 19 is secured to the other end of the shaft 20, and a clutch 49 is provided for operatively connecting and disconnecting the sprocket 19 to the shaft 20.

The sides of the brick molds are formed by L-shaped plates 50 supported by brackets 51 secured to the uprights 33-35 and 34-36, respectively.

Each longitudinal divider bar 21 has at its forward end an apertured upstanding ear 21'. A rod 52 extends through the aligning apertures of the five divider bars and is supported at its ends by brackets 53 secured to the uprights 35 and 36. The divider bars extend upwardly in the slots or spaces 11' between the individual backs 11 of the pallet-carriers and rest on the upper surface of the pallets. From the upstanding ears 21' to just beyond the tamper 27, the height of the divider bars is substantially less than the contemplated thickness of the bricks. Over their remaining length (i. e. from the point just beyond the tamper), the height of the divider bars is slightly greater than the contemplated thickness of the bricks. The upstanding edge 54 of each divider bar, at the point of height change, is forwardly inclined and beveled in order to impart side compression to the brick material as it advances against this beveled edge (Figs. 5 and 7). If desired, the upper horizontal edge 55 of that portion of the divider bar of shorter height may also be beveled (Fig. 6). The height of the divider bars at their forward ends may advantageously be about one-half the contemplated thickness of the finished brick, and the height of the bars over their remaining length may be one-eighth to one-third greater than the contemplated brick thickness.

The mixer blades 24 are shown in detail in Figs. 11, 12 and 13. The blades are generally semi-circular in contour and each is secured to a semi-cylindrical hub 56 provided with an aperture 57 to permit bolting of the hub and attached blade to the shaft 40. When assembled and bolted on the shaft, the blades are angularly inclined for pushing and pressing the brick material from the center outwardly, and hence into the corners of the outer brick molds (on each side) where the downward pressure of the feed (from the hopper) is not adequate to properly fill the corners of those molds.

Two paddles 25 are bolted to the shaft 41. The paddles are circularly concaved at the base to conform with the diameter of the shaft 41 to which they are bolted, and from the base (of greater width than the diameter of the shaft 41) the sides of the paddle extend outwardly to a blunt peak (Fig. 1). In rotating, the paddles exert a rotary tampering and troweling action on the top of the material in the brick molds. In the machine illustrated in the drawings, each paddle spans three brick molds. The shafts 40 and 41, and hence the blades 24 and paddles 25, rotate in opposite directions.

The tamper 27 is a transversely disposed plate

adapted to be vertically reciprocated to impart a rapid tampering action to the material in the molds as they progress beneath the tamper. The tamper plate is suspended from two spaced eccentric bearings mounted on the shaft 42, each bearing comprising an eccentric core 58 fastened to the shaft and rotatably mounted within a sleeve 59. The sleeve has a threaded and hence vertically adjustable connection with a tubular connector 60. A vertically disposed link 61 is pivoted at its upper end to the connector 60 and at its lower end is pivoted to a yoke 62. The two yokes are pivoted to the upper part of the tamper plate in the same spaced relationship as the two eccentric bearings. The axes of the two pivots of the link 61 are parallel with each other and with the axis of the shaft 41, and the reciprocation of the tamper plate is therefore in a substantially vertical plane.

The remaining structural features of the machine can be best described in connection with its operation. Power is supplied to the pulley 43 and is transmitted through the gearing hereinbefore described to move the pallet-conveyor, to rotate the blades 24 and the paddles 25, and to reciprocate the tamper 27. The cementitious or other brick material is fed into the hopper 23 and is pressed by the weight of the feed into the molds formed by the upstanding backs 11, the side plates 50 and the divider bars 21.

The rear wall 23' of the hopper terminates at about the level of the shafts 40-41, so that the molds pass into the rotary troweling and tamping zone with some excess of material. The rotary blades 24 mix and trowel the material and press it into the corners of the outer bricks which the pressure of the hopper feed failed to fill. The rotating blades then exert a combined tamping and troweling action on the material. The molds next pass beneath an adjustable cut-off plate 63 and troweling bar 26.

The bar 26 is generally U-shaped with one upstanding leg secured to the cut-off plate 63, the other upstanding leg forming a sealing guide for the tamper 27, and the intermediate portion being substantially flat and horizontal to exercise the contemplated troweling action as the filled molds pass underneath it. The cut-off plate 63 is attached to the rear wall 64 of the rotary troweling and mixing zone by bolts 65 threaded in spaced lugs 66 and 67 secured to the wall 64 and the plate 63, respectively, thus permitting vertical adjustment of the plate 63. The plate 63 is secured to the wall 64 in its vertically adjusted position by bolts 68 which pass through slots in the plate into threaded holes in the wall.

The molds next pass beneath the rapidly reciprocating tamper 27 which tamps the material therein to approximately the contemplated thickness of the bricks. The cut-off plate 63 is so adjusted as to fill the molds with the amount of material required in the finished brick. The height of this material in the molds, as the latter pass beneath the troweling plate 26, is greater than the contemplated thickness of the brick. The tamper 27 is vertically adjusted to tamp the brick to the contemplated thickness. The lower horizontal or tamping surface of the tamper 27 is relatively narrow in width, the brick length being 10 to 20 times as long as the effective tamping width of the tamper, so that the bricks on each pallet are tamped progressively from their advancing ends to their withdrawing ends as the

pallet passes underneath the tamper, as illustrated in Fig. 1 of the drawings.

The tops of the divider bars 21 are covered with the brick material until the action of the tamper on the material is completed. As the molds pass beyond the tamper 27, the material therein meets the upstanding beveled edge 54 of the divider bars, and the bevel imparts a degree of side compression to the material as it passes into the zone where the height of the divider bars is greater than the thickness of the bricks. Here the molded bricks are subjected to a final troweling by the individual trowels 28.

The trowels 28 extend rearwardly, like the prongs of a fork, from the lower edge of a vertically disposed base plate 28' (Figs. 8, 9 and 10). The base plate forms a sealing guide for the tamper 27 on the side opposite the upstanding leg of the U-shaped bar 26. The rear ends of the trowels 28 are secured to a transverse supporting bar 69 appropriately slotted on its lower edge to span the divider bars 21. The trowels 28 are secured to the stationary side plates 50 (of the brick molds) by off-set brackets 70 which permit adjustment of the angle of contact of the trowels with the upper surface of the material in the molds. At their inner ends the brackets are secured by bolts 71 to the end trowels. The outer ends of the brackets 70 have a wide-angled wedge-shaped contour (Fig. 8) adjacent and contacting the horizontal portion of the L-shaped side plates 50, and are secured to the plates by two spaced bolts 72. By loosening one bolt 72 and tightening the other, the angle at which each bracket 70 is fastened to the plate 50 can be varied to adjust as desired the angle of contact of the trowels 28 with the brick material.

The completely molded bricks now travel to the discharge end of the machine. Mounted for free rotation on the shaft 16 are two spaced pulleys 73. The pulleys 73 are positioned directly beneath the ends of the pallet 13 extending beyond the pallet-carrier, and hence do not interfere with the travel of the carriers. Each pulley 73 is connected by a cable 74 to another pulley (not shown) which is driven so that the cable moves at a slightly faster rate of speed than the pallet-conveyor. The two cables 74 are synchronously driven. As a pallet, loaded with molded bricks, arrives at the discharge end of the machine, the extending ends of the pallet are picked up by the two cables 74 and carried off and away from the machine at such a speed as to clear the pallet-carrier in its movement around the sprocket 15. In this manner, each pallet with its load of molded brick is automatically discharged from the machine and conveyed by the cables 74 to any desired place for subsequent handling.

The improvements of the invention insure filling of the molds with the brick material, and thereby minimize the production of imperfect brick due to unfilled mold corners and other voids in the brick material. The successive tamping and troweling actions impart to the brick material a substantially homogeneous structure of uniform density. The two-height divider bars permit better mixing, troweling and tamping until the brick has attained its final shape, and the final individual troweling of the brick, between relatively higher divider bars, imparts to each brick a finished top surface comparable with the other smooth surfaces in contact with the mold walls.

I claim:

1. In a brick-making machine in which a con-

veyor of pallet-carriers continuously carries removable brick-supporting pallets through various brick-making operations and in which molds for the bricks are formed on each pallet by upstanding transverse backs secured to each pallet-carrier and a plurality of longitudinal and equally spaced stationary divider bars positioned intermediate and similarly spaced from two outer stationary side plates, the improvement which comprises divider bars having a vertical height substantially less than the contemplated thickness of the brick to be molded up to the stage of final brick formation and having a height higher than the contemplated thickness of the brick to be molded beyond said stage.

2. The improvement in a brick-making machine according to claim 1 further characterized in that the height change in each divider bar is abrupt and the upstanding edge of the bar at the point of height change is forwardly inclined and beveled.

3. In a brick-making machine in which a conveyor of pallet-carriers continuously carries removable brick-supporting pallets through various brick-making operations involving feeding, troweling and tamping of the brick material in molds formed on each pallet by upstanding transverse backs secured to each pallet-carrier and a plurality of longitudinal and equally spaced stationary divider bars positioned intermediate and similarly spaced from two outer stationary side plates, the improvement which comprises a vertically adjustable cut-off plate, a vertically reciprocable tamping plate, a horizontally-disposed troweling plate having at its forward end an upstanding flange secured to said cut-off plate and at its rear end an upstanding flange contacting the forward side of said tamping plate, and a plurality of longitudinally extending trowels corresponding in number to the number of molds on the pallet and secured to a common vertically-disposed support contacting the rear side of said tamping plate.

4. In a brick-making machine in which a conveyor of pallet-carriers continuously carries removable brick-supporting pallets through various brick-making operations involving feeding, troweling and tamping of the brick material in molds formed on each pallet by upstanding transverse backs secured to each pallet-carrier and a plurality of longitudinal and equally spaced stationary divider bars positioned intermediate and similarly spaced from two outer stationary side plates, the improvement which comprises a vertically reciprocable tamping plate, said divider bars having a vertical height less than the contemplated thickness of the brick to be molded from their forward ends up to a point just beyond said tamping plate and having a height higher than the contemplated thickness of the brick from that point to their rearward ends, and a plurality of longitudinally extending trowels corresponding in number to the number of molds on the pallet and positioned in the spaces between said divider bars and said side plates with their forward ends at approximately the point of height increase of the divider bars.

5. In a brick-making machine in which a conveyor of pallet-carriers continuously carries removable brick-supporting pallets through various brick-making operations involving feeding troweling and tamping of the brick material in molds formed on each pallet by upstanding transverse back secured to each pallet-carrier and a plurality of longitudinal and equally spaced station-

ary divider bars positioned intermediate and similarly spaced from two outer stationary side plates, the improvement which comprises a vertically adjustable cut-off plate, a vertically reciprocable tamping plate, a horizontally-disposed troweling plate having at its forward end an upstanding flange secured to said cut-off plate and at its rear end an upstanding flange contacting the forward side of said tamping plate, and a plurality of longitudinally extending trowels corresponding in number to the number of molds on the pallet and secured to a common vertically-disposed support contacting the rear side of said tamping plate, said divider bars having a vertical height less than the contemplated thickness of the brick to be molded from their forward ends up to a point just beyond said tamping plate and having a height higher than the contemplated thickness of the brick from that point to their rearward ends.

6. In a brick-making machine in which a conveyor of pallet-carriers continuously carries removable brick-supporting pallets through various brick-making operations involving feeding, troweling and tamping of the brick material in molds formed on each pallet by upstanding transverse backs secured to each pallet-carrier and a plurality of longitudinal and equally spaced stationary divider bars positioned intermediate and similarly spaced from two outer stationary side plates, the improvement which comprises rotary troweling and tamping means proximate but rearwardly of the feed of the brick material, a vertically adjustable cut-off plate rearwardly of said rotary means, a horizontally-disposed U-shaped troweling plate having its forward upstanding leg secured to said cut-off plate, a vertically reciprocable tamping plate with its forward side in contact with the other upstanding leg of said troweling plate, and a plurality of longitudinally extending trowels corresponding in number to the number of molds on the pallet and secured to a common vertically-disposed support contacting the rear side of said tamping plate.

7. In a brick-making machine in which a conveyor of pallet-carriers continuously carries removable brick-supporting pallets through various brick-making operations involving feeding, troweling and tamping of the brick material in molds formed on each pallet by upstanding transverse backs secured to each pallet-carrier and a plurality of longitudinal and equally spaced stationary divider bars positioned intermediate and similarly spaced from two outer stationary side plates, the improvement which comprises rotary troweling and tamping means proximate but rearwardly of the feed of the brick material, a vertically adjustable cut-off plate rearwardly of said rotary means, a horizontally-disposed U-shaped troweling plate having its forward upstanding leg secured to said cut-off plate, a vertically reciprocable tamping plate with its forward side in contact with the other upstanding leg of said troweling plate, a plurality of longitudinally extending trowels corresponding in number to the number of molds on the pallet and secured to a common vertically-disposed support contacting the rear side of said tamping plate, said divider bars having a vertical height less than the contemplated thickness of the brick to be molded from their forward ends up to a point just beyond said tamping plate and having a height higher than the contemplated thickness of the brick rearwardly beyond that point, a movable pallet-supporting device proximate the dis-

charge end of the machine and upon which the advancing end of the next pallet to be discharged from the machine is adapted to be pushed by the movement of the pallet-conveyor, and means for moving said pallet-supporting device in a direction away from the discharge end of the machine at a higher rate of speed than that of the pallet-conveyor.

8. In a brick-making machine in which a conveyor of pallet-carriers continuously carries removable brick-supporting pallets through various brick-making operations involving feeding, troweling and tamping of the brick material in molds formed on each pallet by upstanding transverse backs secured to each pallet-carrier and a plurality of longitudinal and equally spaced stationary divider bars positioned intermediate and similarly spaced from two outer stationary side plates, the improvement which comprises a plurality of blades mounted on a rotary shaft proximate but rearwardly of the feed of the brick material, the blades on one part of the shaft having a contour and angular disposition to push the brick material toward the adjacent side plate and the blades on the other part of the shaft having a

5

contour and angular disposition to push the brick material toward the other side plate as the shaft rotates, and a tamping paddle spanning several brick molds and mounted on a rotary shaft proximate but rearwardly of the rotary shaft carrying the blades.
